SCREEN CLEANING GUN

Clarence A. Ricou, Shreveport, La., assignor to
Petroleum Increase Corporation, Carthage,
Tex., a corporation of Texas

Application October 9, 1939, Serial No. 298,725

1 Claim. (Cl. 166—20)

My invention relates to oil, gas wells and the like, and includes among its objects and advantages the provision of an improved screen or liner gun for such wells.

Well casing screens or liners become impaired through the accumulation of various materials which block the fluid from entering the well or casing. Frequently such accumulations are highly abrasive in their character and would cause considerable damage to the pumping equipment if they were not strained from the fluid. Various types of screens have been employed to exclude such material from entry into the pumping system, but cleaning of the screens has entailed considerable work and expense.

Accordingly, an object of my invention is to provide a gun designed to utilize explosive forces effective on a column of fluid for forcing the fluid through the screen or liner to effectively remove accumulations thereon so as to increase the production of the well. In my invention, the fluid column reacted by the explosive forces constitutes a projectile which effectively removes accumulations from the well screen or liner.

In the accompanying drawing:

Figure 1 is an elevational view of a gun in accordance with my invention;

Figure 2 is a sectional view along the line 2—2 of Figure 1;

Figure 3 is a detail view of a go-devil which may be employed for firing the gun; and

Figure 4 is a sectional detail view illustrating a line means which may be employed for lowering the gun into a well in combination with a different form of firing mechanism.

In the embodiment selected to illustrate my invention, the gun 10 comprises a cylindrical body 12, bored at 14 to provide a powder chamber, which bore terminates in a larger bore 16 for the reception of a projectile 18. Projectile 18 includes a cylindrical body 20 pressed into the projectile bore 16, and the projectile includes a tapered nose 22.

Between the shoulder 24 and the rear face of the projectile 18 I position a lead plate 26 which constitutes a seal for the powder chamber 14. Coaxially with the projectile bore 16 I provide a larger bore 28 within which I position a lead washer 30 having a central opening fitting tightly against the tapered nose 22. Between a metal washer 32 and the lead washer 30 I position a copper gasket 34, with the iron ring and the gasket having central openings through which the nose of the projectile extends. A clamp ring 55

36 is threaded into the bore 28, as at 38 for the application of pressure to the washers 30, 32 and 34 for the purpose of urging the projectile against the sealing plate 26, thus effectively anchoring the projectile in addition to providing an effective seal so as to prevent the entrance of moisture into the powder chamber.

A powder bore or train 40 establishes communication between the powder chamber 14 and the lower part of a bore 42 extending inwardly of the upper end of the body 12. Bore 42 is internally threaded at 44 for the reception of a sleeve 46 having a wall 48 spaced slightly from the bottom of the bore 42 to provide a space 50 for powder or other suitable explosive material, which is also contained in the powder chamber 14 as well as the bore 40.

Wall 48 is provided with two bores 52 for the reception of primer caps 54. Inside the sleeve 46 I position a retaining collar 56 having a bore 58 loosely receiving the head 60 of a firing pin assembly 62 having pins 64 adapted to be driven into the primer caps 54 for firing the latter.

Head 60 terminates in a taper 66 lying adjacent a corresponding taper 68 in the collar 56, and the collar includes a bore 70 loosely receiving the shank 72 of the firing pin assembly. Normally the firing pin assembly 62 is held out of firing engagement with the primer cap 54 through the medium of a shear pin 74. A short tube 76 has its lower end threaded into the bore 42 and is provided with a threaded neck 78 for connection with tubing 80 through the medium of a coupling member 82.

In operation, the gun 10 may be lowered into the well through the medium of a tubing 80. When the gun has been properly positioned, it is fired through the medium of a go-devil 84 which is dropped into the tubing 80 for striking the shank 72 to shear the pin 74 and drive the firing pins 64 into the primer caps 54. Go-devil 84 is provided with a leading tapered nose 86 to facilitate penetration of discs 88 welded inside a perforated section 90 in the tubing 80. The gun is positioned in the well at the top of the liner or screen associated with the casing, or inside the liner or screen. As the explosion occurs, the projectile 18 is fired from the gun which causes the fluid in the well to be converted into a projectile, and the fluid is driven downwardly and outwardly of the screen or liner with such force as to effectively clear all the openings of the screen or liner. The fluid is forced through the screen or liner and penetrates into the formation

in all directions, thus altering the sands and breaking down other obstructions so as to permit a free flow of fluid or gas into the bore hole for recovery through conventional production methods.

The discs 88, before being perforated by the go-devil 84, seal the perforated section 90 from the remainder of the tubing 80 as well as the tube 76. Thus the gun is effectively sealed at its upper end. Perforation of the discs 88, particularly the upper disc, permits the fluid to rush into and upwardly of the tubing 80 which places a vacuum on the sands or other formation to increase the productivity of the well. Thus the gun as well as the tubing 80 may be left in place after firing so that the tubing 80 may be utilized for production purposes. Go-devil 84 is provided with a spiral groove 92 which facilitates passage of the fluid between the go-devil and the tubing.

Firing of the explosive in the chamber 14 will cause the projectile 18 to rupture the washers 30, 32 and 34, but before such rupture, these washers in connection with the sealing plate 26 effectively seal the powder chamber against the entrance of moisture.

My invention completely eliminates the necessity of removing screens and liners for cleaning purposes. Attempts have been made to run tools into such liners and screens but such tools have frequently cut and otherwise damaged the screens and liners so as to necessitate substitutes of liners and screens which entail considerable labor and expense.

In Figure 4 I illustrate a different mechanism for lowering the gun into the well. The gun body 12 is identical with that illustrated in Figure 2, which is also true of the firing pin assembly 62. Sleeve 94 differs from the sleeve 46 in that it is devoid of threads, but the collar 56 and the shear pin 96 remain the same. A coupling element 98 is threaded into the bore 100 which corresponds to the bore 42 and the inner end of the coupling member engages the collars 56 and 94 for holding the latter in place.

Coupling member 98 is provided with an enlarged bore 102 for accommodation of the shank 72, and the member is bored at 104 for the reception of a cable or rope 106 having a connecting

element 108 disposed in the enlargement 110 of the bore 104. Member 98 is also provided with two bores 112 for the reception of rods 114 normally held in position of Figure 4 through the medium of frangible welds 116. The upper ends of the rods are fixedly related to a ring 118 through which the rope or cable 106 passes. A go-devil in the nature of a heavy tubular element 120 is guided downwardly by the rope or cable for striking the ring 118, to break the welds 116 and drive the rods 114 onto the firing pin assembly 62. Thus the rods 114 are driven against the firing pin assembly to shear the pin 96, which in turn fires the primer caps 54. Welds 116 provide a seal, which is also true of the metallic coupling element 108.

Having thus described certain embodiments of my invention in detail, it is, of course, understood that I do not desire to limit the scope thereof to the exact details set forth except insofar as those details may be defined in the appended claim.

What is claimed is:

A gun of the type described adapted to be lowered into a perforated liner comprising a body having a longitudinal bore constituting an explosion chamber, said bore extending through the lower end of the body, a closure means for the lower end of said bore, a firing bore communicating with said explosion chamber, explosive material in said firing bore and said explosion chamber, means for firing the explosive adjacent said firing bore for firing the explosive in said explosion bore to rupture said closure means and direct the forces of explosion into the fluid adjacent said liner for removing accumulations thereon, said firing means including a plurality of primer caps and impact responsive firing pins for firing the caps, a tubular member for lowering the gun, including a perforated section in the tubular member, sealing discs inside said perforated section for sealing the tubular member and said gun, and a go-devil for rupturing said discs and for striking said firing pins, said perforated section constituting an inlet for fluid after rupturing of at least one of said discs to permit the fluid to rise in said tubular member.

CLARENCE A. RICOU.
